US00D942096S

(12) **United States Design Patent** (10) Patent No.: **US D942,096 S**
Tang et al. (45) Date of Patent: ** *Jan. 25, 2022

(54) **MULTIFUNCTIONAL UNDERWEAR STERILIZER**

(71) Applicant: **LEADYOUNG TECHNOLOGY CO., LTD.**, Shenzhen (CN)

(72) Inventors: **Iven Tang**, Shenzhen (CN); **Michael Zhang**, Shenzhen (CN)

(73) Assignee: **LEAD YOUNG TECHNOLOGY CO., LTD.**, Shenzhen (CN)

(*) Notice: This patent is subject to a terminal disclaimer.

(**) Term: **15 Years**

(21) Appl. No.: **29/650,367**

(22) Filed: **Jun. 6, 2018**

(51) LOC (13) Cl. **15-05**

(52) U.S. Cl.

(57) **CLAIM**

We claim the ornamental design for a multifunctional underwear sterilizer, as shown and described.

DESCRIPTION

FIG. 1 is a perspective view of a multifunctional underwear sterilizer, showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top elevation view thereof; and,

FIG. 7 is a bottom elevation view thereof.

1 Claim, 4 Drawing Sheets
